REFRIGERATING APPARATUS

James W. Jacobs, Dayton, Ohio, assignor to General Motors Corporation, Dayton, Ohio, a corporation of Delaware

Application November 12, 1940, Serial No. 365,324

9 Claims. (Cl. 62—89)

This invention relates to refrigerating apparatus and particularly to household refrigerators.

In household refrigerating apparatuses, the cabinet thereof is usually provided with an insulated food storage chamber containing an evaporator of a closed refrigerant circulating system and a machine compartment located below the food chamber for housing the refrigerant circulating unit that is connected to the evaporator of the closed refrigerating system. The refrigerant circulating unit within the machine compartment compresses and liquefies refrigerant within the closed system. Others have provided a drawer or bin at the front of the machine compartment and have set forth that the drawer or movable bin is intended for utilization as a reserve storage for fruits and vegetables. Up to the present time, however, such storage drawers or bins have not been entirely satisfactory because the user of a refrigerator equipped with the same has found that heat generated by the refrigerant liquefying and circulating unit soon dries out many food products placed in the drawer or bin. For example, the temperature within a machine compartment of a refrigerator cabinet often rises to 110° F. and therefore potatoes, beets, turnips, onions, apples, pears and other food products placed in the reserve storage drawer or bin associated with the machine compartment is heated far above room temperature by heat generated by the refrigerant liquefying and circulating unit. Thus the user of a refrigerating apparatus equipped with a storage drawer or bin exposed to the heat of the machine compartment has been compelled to employ the drawer or bin for the storage of such articles as pots, pans, and other kitchen utensils instead of food products. My invention is therefore directed to the making of a storage bin associated with the machine compartment of a household refrigerating apparatus practical for the proper storage of food products.

An object of my invention is to provide an improved household refrigerating apparatus having a storage bin associated with the machine compartment of the refrigerator cabinet by permitting air to circulate through the bin whereby food products stored therein will be properly ventilated and prevented from absorbing heat from the refrigerating unit mounted in the machine compartment.

Another object of my invention is to provide a household refrigerating apparatus with a food storage bin associated with the machine compartment thereof which bin is so constructed and

arranged that cool air from the refrigerator food storage chamber of the refrigerator cabinet will flow into the bin to cool and ventilate the contents when the door providing access to the food chamber is opened.

10 A further object of my invention is to provide a refrigerator cabinet wherein air circulating through the machine compartment thereof, to remove heat from the refrigerant liquefying and circulating unit of the refrigerating system associated with the cabinet, is utilized to ventilate food products stored in a bin located within a portion of the machine compartment.

15 A still further object of my invention is to provide a storage bin within a refrigerator cabinet that is continuously ventilated by air circulating therethrough and which bin projects outwardly from the front wall of the cabinet and is provided with an open top portion, normally 20 closed by the door of the refrigerated food storage chamber and opened or uncovered by movement of the door into its open position, for permitting cool air from the food chamber to flow into the bin to cool and ventilate the contents thereof.

25 In carrying out the foregoing objects, it is a more specific object of my invention to provide a food storage bin at the front of a machine compartment of a household refrigerator cabinet 30 which bin is provided with apertures in a bottom wall portion, projecting beyond the cabinet front wall, and apertures in its inner wall for permitting air exteriorly of the cabinet to flow into the bin at a point adjacent the bottom of 35 the cabinet and thence through the bin and the machine compartment for ventilating the interior of the bin and for removing heat from the machine compartment.

40 Further objects and advantages of the present invention will be apparent from the following description, reference being had to the accompanying drawing, wherein a preferred form of the present invention is clearly shown.

45 In the drawing:

45 Fig. 1 is a front view of a household refrigerator cabinet having my invention embodied therein and showing the door to the refrigerated food storage chamber in open position;

50 Fig. 2 is a side view of the refrigerator cabinet disclosed in Fig. 1;

Fig. 3 is an enlarged vertical sectional view of the refrigerator cabinet taken on the line 3—3 of Fig. 1 showing a food storage bin associated with the machine compartment thereof; and

Fig. 4 is a horizontal sectional view taken on

the line 4—4 of Fig. 3 showing apertures in walls of the storage bin.

Referring to the drawing, I show in Fig. 1 thereof a refrigerating apparatus in the form of a household refrigerator cabinet generally represented by the reference character 10. Cabinet 10 includes a plurality of metal walls 11 forming an outer shell or wall surfaces of the cabinet and a liner member 12 within the upper portion of the cabinet surrounded by any suitable insulating material 14 (see Fig. 3) and forming walls of a food storage chamber 15. The walls 11 extend downwardly beyond the insulated chamber 15 to enclose a machine compartment 16 at the bottom of cabinet 10. Front wall 11 of cabinet 10 and the front of liner member 12 each have an opening therein registering with one another to provide an access opening leading to the interior of chamber 15. An insulated door structure 18, having a portion 19, extending into the access opening of chamber 15, and a wider edge portion 21 overlapping the access opening of chamber 15 and engaging the cabinet front wall 11, normally closes the chamber 15. Door 18 is pivotally mounted about a vertical axis upon the front of cabinet 10 and swings horizontally to open the access opening of the chamber 15. The back wall 11 of machine compartment 16 is provided with an aperture 23 therein (see Fig. 3) and the front wall 11 has an opening 24 provided therein (see Fig. 4). Other walls 11 of cabinet 10 close the sides of the machine compartment 16 and this compartment is closed at its bottom by the floor upon which the refrigerator cabinet rests. An evaporator 25 of a closed refrigerating system is mounted within cabinet 10 and located in the upper portion of the food storage chamber 15. Evaporator 25 is connected with a motor-compressor unit 26 by a conduit 27 and with a condenser 28, forming a part of the unit, by a conduit 29. The elements 26 and 28 form a refrigerant compressing and liquefying unit, mounted upon suitable mounting brackets within the machine compartment 16, and this unit draws evaporated refrigerant from evaporator 25, through conduit 27, into the motor-compressor where it is compressed and forwarded, through a conduit 31, to the condenser 28. Condenser 28 is preferably vertically disposed in the space provided by the aperture 23 in the back wall 11 of compartment 16 and a flue forming member 30 is secured to the cabinet back wall for a purpose to be hereinafter more fully described. Heat is removed from the condenser, in a manner to be presently described, for liquefying the compressed refrigerant and the liquefied refrigerant is circulated through conduit 29 to the evaporator 25, for vaporization therein to cause the evaporator to produce a refrigerating effect within the food storage chamber 15. The refrigerating effect produced by evaporator 25 cools and causes circulation of air within the chamber 15 to preserve food products stored in this chamber. Refrigerated chamber 15 may be divided into superimposed food storage spaces by a plurality of shelves 33 upon which the food may be supported. Any conventional control device 34, mounted upon the unit 26, may have electrical connections with a suitable switch (not shown) actuated in response to the temperature produced by the evaporator 25 for controlling the starting and stopping of the motor-compressor as is well known in the art.

In the present disclosure of a food storage bin-like element, represented as a whole by the ref-

erence character 35 is pivotally mounted by hinges 36 upon the front wall 11 of cabinet 10 (see Fig. 3). Bin-like element 35 comprises a front wall 37, a back wall 38, a bottom wall 39 and two side walls 41. The bin 35 is mounted so that its front portion extends outwardly beyond the front wall 11 of cabinet 10 and is provided with a handle or knob 42 for facilitating movement of same about its pivotal mountings 36. Bin element 35 forms a cover for closing the opening 24 in the front wall of machine compartment 16 of the refrigerator 10. A bracket 43 secured to the under side of the bottom wall of chamber 15 forms a stop for the inward movement of bin 35 to thereby maintain the bin in the projected position described. A bracket 44 may be secured to the front portion of compartment 16 and disposed in the path of movement of the back wall 38 of bin 35 so as to be engaged by this wall 38 for preventing the bin from moving outwardly of compartment 16, about its pivotal mounting beyond the fully open position thereof indicated by the dot-dash lines in Fig. 3, of the drawing. Front wall 37 of bin 35 is disposed substantially in the same vertical plane with the outer face of the food chamber door 18. The open top of bin 35 or at least that portion of its top which projects outwardly beyond the front wall of cabinet 10 is normally covered or concealed by the bottom edge portion 21 of door 18 when this door is in its closed position. A plurality of substantially round spaced apart apertures 46 are provided in the back wall 38 of the bin element 35 and a plurality of spaced apart elongated apertures 47 are provided in the projecting bottom wall portion 39 of the bin.

According to the present invention, the interior of the bin-like element 35 is continuously ventilated and various food products may be stored therein without danger of absorbing heat from the machine compartment 16 and being dried out. In the normal use of the apparatus, food products of various kinds are stored within the bin 35 and air, of a temperature of from 65° to 75° F., from the room in which the refrigerator 10 is located, circulates through the apertures 47 in the bottom wall 39 of bin 35, into the bin and around foods therein and out of the bin 35 through the apertures 46 in its back wall 38. The air entering the machine compartment 16 through the bin 35 sweeps over the motor-compressor 26 and over the condenser 28 in its passage out of the compartment 16 through the aperture 23 in its back wall 11. Air flowing from compartment 16 enters the flue 30 wherein it rises and flows therefrom back into the room. This thermo-syphon circulation of air takes place due to the relatively low temperature of air exteriorly of compartment 16 near the floor or at the entrance to the bin, as compared to the higher temperature, say for example, 90° to 100° F. of air within compartment 16 and caused by heat generated by the refrigerant circulating unit disposed therein. It is, of course, to be understood that a fan could be mounted within the machine compartment 16 and operated simultaneously with operation of motor-compressor 26 to augment this air circulation or to force the air through the bin 35 and machine compartment 16 without departing from the spirit of the present disclosure. The substantially continuous flow of air through bin 35 and machine compartment 16 ventilates the contents of the bin and maintains food products stored therein at approximately room temperature. In other words,

the contents of bin 35 are prevented, by air circulating through the bin, from absorbing the high temperature of compartment 16 and the food products are thereby prevented from being dried out by heat generated by the refrigerant liquefying and circulating unit.

In addition to the continuous flow of air through bin 35 and around foods stored therein, my invention provides for the cooling of the contents of the bin when the door 18 of the refrigerated food chamber 15 is opened. As before stated, the door 18, when in its position to close the access opening of chamber 15, normally closes or conceals the open top portion of bin 35 which projects outwardly beyond the front wall 11 of cabinet 10 and when this door 18 is opened, the projecting open top portion of bin 35 is normally disposed in the path of cold air which escapes from the refrigerated food chamber 15. The cold air escaping from chamber 15, when door 18 is opened flows downwardly around the front edge of the bottom wall of chamber 15 through the open top projecting portion of bin 35 into the bin to cool the contents thereof and to aid in ventilating food products stored in the bin. Cool air circulating into the bin may flow out of the bin through either of the sets of apertures 46 and 47 in the walls thereof. Cool air flowing through the apertures 46 in the back wall 38 of bin 35 absorbs heat from compartment 16, motor-compressor 26 and condenser 28, and flows outwardly of the compartment through the aperture 23 in its back wall into the flue 30 and upwardly therethrough.

From the foregoing it will be apparent that I have provided an improved household refrigerating apparatus wherein food products stored in a bin disposed in the machine compartment thereof are prevented from absorbing heat from the refrigerant liquefying and circulating unit located in the compartment and are thereby prevented from being dried out by such heat. My invention renders an auxiliary or reserve food storage bin in a refrigerator cabinet practical and usable for the proper storage of foods and eliminates the old practice of utilizing such a bin for the storage of pots, pans and other kitchen utensils. By ventilating a reserve food storage bin in the manner herein disclosed, foods stored therein are maintained substantially at room temperature and will not attain such a high temperature as is frequently found to be existing within the machine compartment. The feature of permitting cold air which escapes from the lower portion of the refrigerated chamber, when the access door thereto is periodically opened, to flow into the vegetable storage bin, cools the contents thereof below the temperature of the air in the room in which the refrigerator cabinet is located insures proper ventilation and preservation of foods placed in a storage bin disposed beyond the refrigerated chamber.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising in combination, a cabinet having a plurality of walls forming a food storage chamber therein and a machine compartment below the food chamber, an evaporator of a closed refrigerating system mounted within said cabinet for cooling the food storage chamber, a refrigerant liquefying unit

5 mounted within said machine compartment and connected to said evaporator for circulating a refrigerating fluid therethrough, said food storage chamber being provided with an access opening 10 in the front thereof, a door for normally closing said chamber access opening, the front wall of said machine compartment having an opening 15 therein, a bin-like element movably mounted upon said cabinet and forming a cover for the opening in said machine compartment wall, the front of said bin-like element being located outwardly beyond the front wall of said cabinet, at least that portion of the top of said element located beyond the front wall of said cabinet being open, and said open top portion of said element being substantially closed by a bottom edge of said door when the door is in its closed position and opened when said door is moved into open position to permit cool air from said food chamber to flow into said bin-like element for cooling the contents thereof.

2. A refrigerating apparatus comprising in combination, a cabinet having a plurality of walls forming a food storage chamber therein and a machine compartment below the food chamber, an evaporator of a closed refrigerating system mounted within said cabinet for cooling the food storage chamber, a refrigerant liquefying unit mounted within said machine compartment and connected to said evaporator for circulating a refrigerating fluid therethrough, said food storage chamber being provided with an access opening in the front thereof, a door for normally closing said chamber access opening, the front wall of said machine compartment having an opening therein, a bin-like element movably mounted upon said cabinet and forming a cover for the opening in said machine compartment wall, the front wall of said bin-like element being located outwardly beyond the front wall of said cabinet, other wall portions of said element having openings therein, at least that portion of the top of said element located beyond the front wall of said cabinet being open, and said open top portion of said element being substantially closed by a bottom edge of said door when the door is in its closed position and opened when said door is moved into open position to permit cool air from said food chamber to flow into said bin-like element and outwardly therefrom through the openings in said other wall portions thereof.

3. A refrigerating apparatus comprising in combination, a cabinet having a plurality of walls forming a food storage chamber therein and a machine compartment below the food chamber, an evaporator of a closed refrigerating system mounted within said cabinet for cooling the food storage chamber, a refrigerant liquefying unit mounted within said machine compartment and connected to said evaporator for circulating a refrigerating fluid therethrough, said food storage chamber being provided with an access opening in the front thereof, a door for normally closing said chamber access opening, the front wall of said machine compartment having an opening therein, another wall of said machine compartment being provided with an aperture therein, a bin-like element movably mounted upon said cabinet and forming a cover for the opening in the front wall of said machine compartment, the front wall of said bin-like element being located outwardly beyond the front wall of said cabinet, at least that portion of the top of said element located beyond the front wall of said cabinet being open, the inner wall

of said element having apertures therein, and said open top portion of said element being substantially closed by a bottom edge of said door when the door is in its closed position and opened when said door is moved into open position to permit cool air from said food chamber to flow into said bin-like element and outwardly thereof through the apertures in its inner wall into said compartment and thence outwardly of the compartment through the aperture in said another wall thereof.

4. A refrigerating apparatus comprising in combination, a cabinet having a plurality of walls forming a food storage chamber therein and a machine compartment beyond the food chamber, an evaporator of a closed refrigerating system mounted within said cabinet for cooling the food storage chamber, a refrigerant liquefying unit mounted within said machine compartment and connected to said evaporator for circulating a refrigerating fluid therethrough, one side wall of said machine compartment having an aperture therein and another side wall thereof being provided with an opening, a bin-like element movably mounted upon said cabinet and forming a cover for the opening in said another wall of the machine compartment, and said bin-like element being so constructed and arranged as to permit air exteriorly of said cabinet to circulate therethrough into said machine compartment and outwardly of the machine compartment through the aperture in its said one side wall whereby the circulating air ventilates the interior of said element and removes heat from said machine compartment.

5. A refrigerating apparatus comprising in combination, a cabinet having a plurality of walls forming a food storage chamber therein and a machine compartment below the food chamber, an evaporator of a closed refrigerating system mounted within said cabinet for cooling the food storage chamber, a refrigerant liquefying unit mounted within said machine compartment and connected with said evaporator for circulating a refrigerating fluid therethrough, the back wall of said machine compartment having an aperture therein and the front wall thereof being provided with an opening, a bin-like element movably mounted upon said cabinet and forming a cover for the opening in said compartment front wall, at least a portion of the bottom of said bin-like element being located outwardly beyond the front wall of said cabinet, said portion of the bottom of said element being disposed above the bottom of said cabinet and having apertures therein, the inner wall of said element also having apertures therein, and said apertures in said element permitting air from exteriorly of said cabinet to circulate through said bin-like element into said machine compartment and outwardly thereof through the aperture in its back wall.

6. A refrigerating apparatus comprising in combination, a cabinet having a plurality of walls forming a food storage chamber therein and a machine compartment below the food chamber, an evaporator of a closed refrigerating system mounted within said cabinet for cooling the food storage chamber, a refrigerant liquefying unit mounted within said machine compartment and connected to said evaporator for circulating a refrigerating fluid therethrough, said food storage chamber being provided with an access opening in the front wall of said cabinet, a door for normally closing said chamber access opening, 75

the back wall of said machine compartment having an aperture therein and the front wall thereof being provided with an opening, a bin-like element movably mounted upon said cabinet and forming a cover for the opening in the front wall of said compartment, the front wall and at least a part of the bottom of said element being located outwardly beyond the front wall of said cabinet, at least the top portion of said element outwardly beyond the cabinet front wall being open and normally closed by a bottom edge of said door, said bottom part of said element being disposed above the bottom of said cabinet and having apertures therein, the inner wall of said element also having apertures therein, the apertures in said bottom part and said inner wall of said element permitting air from exteriorly of said cabinet to circulate through said element into said machine compartment and outwardly thereof through the aperture in its back wall, and said door when moved from its normally closed position into open position uncovering the open top portion of said element to permit cool air from said food chamber to flow thereinto.

25 7. A refrigerating apparatus comprising in combination, a cabinet having a plurality of walls forming a food storage chamber therein and a compartment beyond the food chamber, an evaporator of a closed refrigerating system mounted within said cabinet for cooling the food storage chamber, said food chamber being provided with an access opening in the front thereof, a door for normally closing said chamber access opening, the front wall of said compartment having an opening therein, a bin-like element movably mounted upon said cabinet and forming a cover for the opening in the front wall of said compartment, the front portion of said bin-like element being located outwardly beyond the front wall of said cabinet, that portion of the top of said element located beyond the front wall of said cabinet having an opening therein, that portion of the bottom of said element located beyond the front wall of said cabinet having an opening therein, one of the openings in said element permitting air exteriorly of said cabinet to enter said element for ventilating the interior thereof, and the other of the openings in said element being substantially concealed by an edge of said door when the door is in its closed position.

8. A refrigerating apparatus comprising in combination, a cabinet having a plurality of walls forming a food storage chamber therein and a compartment below the food chamber, an evaporator of a closed refrigerating system mounted within said cabinet for cooling the food storage chamber, said food chamber being provided with an access opening in the front thereof, a door for normally closing said chamber access opening, the front wall of said compartment having an opening therein, a bin-like element movably mounted upon said cabinet and forming a cover for the opening in the front wall of said compartment, the front portion of said bin-like element being located outwardly beyond the front wall of said cabinet, that portion of the top of said element located beyond the front wall of said cabinet having an opening therein, that portion of the bottom of said element located beyond the front wall of said cabinet having an opening therein, the opening in said portion of the bottom of said element permitting air exteriorly of said cabinet to enter said element for ventilating the interior thereof, and the opening

in said portion of the top of said element being substantially closed by the lower edge of said door when the door is in its closed position and opened when said door is moved into open position to permit cool air from said food chamber to flow into said bin-like element for cooling the contents thereof.

9. A refrigerator including walls forming a compartment, a heat dissipating member of a refrigerating system in said compartment, one 10 wall of said compartment having an aperture

therein and another wall thereof having an opening therein, cover means for the opening in the second mentioned wall, said cover means comprising a bin-like element having openings 5 therein, whereby air may circulate through said element into said compartment and outwardly of the compartment through the aperture in its one wall for ventilating the interior of said element and for cooling said member.

JAMES W. JACOBS.
